UNITED STATES PATENT OFFICE.

LOUIS M. DU COMMUN, OF CLEVELAND, OHIO.

AIR-CONDITIONING SYSTEM.

1,132,246.

Specification of Letters Patent. Patented Mar. 16, 1915.

Application filed March 3, 1913. Serial No. 751,704.

To all whom it may concern:

Be it known that I, LOUIS M. DU COMMUN, a citizen of the United States of America, residing at Cleveland, in the county of Cuyahoga and State of Ohio, have invented 5 certain new and useful Improvements in Air-Conditioning Systems; and I hereby declare the following to be a full, clear, and exact description of the invention, such as will enable others skilled in the art to which 10 it pertains to make and use the same.

This invention relates to new and useful improvements in air-conditioning systems.

One object of this invention is to provide 15 an air conditioning system which can be readily installed in auditoriums, school-rooms, work-shops and drying-rooms, and which will thoroughly purify the air and at the same time supply to the 20 air the proper amount of moisture, so that the air will have the requisite degree of humidity according to the need of the place in which the system is installed.

A further object of my invention is to 25 provide a system of this kind which can be cheaply installed, positively regulated and easily cleaned and kept in a sanitary condition.

My invention, therefore, consists in the 30 features of construction and combination and arrangement of parts, the preferred form of which is illustrated in the accompanying drawings, described in the specification and pointed out in the claims.

35 In the accompanying drawings Figure 1 is a vertical section through a room provided with my air-conditioning system. Fig. 2 is an enlarged detail view showing the water troughs and the arrangement of 40 the water supply pipes.

Again referring to the drawings 10 represents the floor of a room, which may be a public-hall, a work-shop or a drying-room of a factory. 11 and 12 represent the outer 45 side walls and 13 represents the ceiling. Within the room and adjacent to this side walls 11 and 12 and spaced a predetermined distance therefrom are arranged partitions or false walls, shown at 14 and 15, and a 50 top partition or false ceiling, shown at 16, said top partition 16 being spaced a predetermined distance from the ceiling 13 of the room. There is, therefore, formed at 55 one side of the room proper an air space, indicated at 20, which for convenience we will term the air-flue, and at the opposite

side of the room an air-space, indicated at 21, which we shall term the purifying chamber, and at the top of the room an air-space, indicated at 22, which communicates with 60 both the flue and the purifying chamber, and which we shall simply designate as a passageway. Near the bottom of the flue 20 are preferably arranged heating-coils 24, and below the said coils in the outer wall of 65 the room are formed air-inlet openings, indicated at 25, the object of which is to permit the entrance of fresh-air from outside of the room into the flue 20. Any suitable arrangement or hood 26 may be provided 70 around the said opening 25 to protect said opening and provide means for regulating the admission of air through said opening. In the inner wall 14 which forms the inner 75 wall of said flue 20 are formed a number of openings 27, one series of said openings being arranged near the floor of the room and the other series of said openings being arranged a predetermined distance above the lower openings, according to the height of 80 the room. In the purifying chamber 21 are arranged a series of water troughs, shown at 85 30, which are supported in any suitable manner. Each trough extends practically the full length of the purifying chamber 90 and has a width somewhat less than the width of the said chamber. These troughs 95 are mounted one above the other and are spaced a short distance apart vertically and are arranged in a staggered formation, the 100 alternate troughs, starting from the topmost trough, being arranged close to the outer wall of the chamber and the other troughs being arranged close to the inner wall of the chamber. This arrangement completely 105 cuts off any circulation of air between the walls and the troughs adjacent thereto, the only passageway for the air being formed by the vertical spaces between the troughs 110 and the spaces between each trough and the wall of the chamber farthest from the trough. It will therefore be seen that the air passing down through the said chamber must follow a sinuous course which carries it alternately from side to side of the chamber and as it passes from side to side it passes over the top of a trough so that when it reaches the bottom of the air chambers it has been carried over the top of all the troughs in the chamber. A water supply 110 pipe 31 is provided which communicates with the uppermost trough. A vertical drain

pipe 32 is arranged near one end of said purifying chamber and this pipe 32 is connected by means of branches 33 with the bottom of each trough, and each of the said branches 33 is provided with a valve 34. Each of the troughs 30, starting at the top, is connected with the next lowermost trough by means of an overflow pipe 34^a which communicates with the upper edge of the 10 uppermost trough, and the bottom trough is connected by an overflow pipe 35 with the drain pipe 32.

While my invention can be successfully applied wherever it is necessary to condition 15 or purify the air in a building or room it is particularly adapted for use in factories or work-shops where volatile liquids or materials are employed, such as benzin, turpentine and acids, and where considerable 20 smoke or fumes are generated. My description of the operation will therefore have particular reference to such cases.

The water troughs are filled with water or other suitable liquid through the pipe 25 system already described and the valves 34 in the branch drain pipes 33 are closed so as to retain the water in said troughs. The air in contact with the heating coils will be raised in temperature and will pass up 30 through the flue 20 drawing in the foul air from the room and also some fresh air from outside. The air will then travel across or through the passageway 22 at the top of the room and enter the purifying chamber. 35 As soon as the air strikes the first trough filled with water the temperature of the air will be lowered and the air will therefore sink rapidly through the purifying chamber. As the air passes through the purifying 40 chamber it must traverse the surface of the water in the various troughs and being thus forced into intimate contact with the water all the impurities carried by the air will be absorbed therefrom and left on the 45 surface of the water. Water is constantly supplied through the pipe 31 to the uppermost trough from which the water overflows into the next lower trough and so down through the whole series of troughs, carrying 50 away any scum or dirt from the surface of the water in the trough, and a clean surface of water is therefore continually presented to the air. It will be understood that as the air passes over the troughs it will, of 55 course, pick up a certain amount of moisture so that when the air again re-enters the room through the opening at the bottom of the chamber 21 the air will not only have been purified but will also have the proper degree 60 of humidity necessary for the comfort and health of the occupants of the room. It will be further noted that by being able to supply any degree of humidity to the air I am able to apply my system very successfully to drying-rooms of paint-shops, and the like, for 65

as is known to those conversant with the art, the quickest and best results, in the drying of all materials containing volatile oils and the like, are obtained when a certain amount of humidity prevails in the air of the drying-room, as the moisture in the air prevents an outer crust from being formed on the paint before the innermost portion has become oxidized or dried.

What I claim is:—

1. In an air-conditioning system, the combination with a room or other inclosed space of a vertically arranged flue, said flue communicating at its lower end with the interior of the room, a purifying chamber, a passageway connecting the upper end of said flue with the upper end of the purifying chamber, a series of vertically spaced water troughs arranged in said purifying chamber, the lower end of said purifying chamber being arranged in communication with the interior of said room and means arranged in said flue for heating the air in said flue to produce an upward movement of air through said flue.

2. In an air-conditioning system, the combination with a room or other inclosed space of a vertically arranged flue communicating at its lower end with the interior of said room, a purifying chamber arranged to communicate at its lower end with the interior of said room, a passageway connecting the upper end of said flue with the upper end of the purifying chamber, a series of superimposed and vertically spaced water troughs arranged in said purifying chamber, the alternate troughs beginning at the upper end of the purifying chamber being arranged in close proximity to one wall of the purifying chamber and the other troughs being arranged in close proximity to the opposite wall of the purifying chamber, said troughs overlapping at the center of said chamber and means for producing a circulation of warm air upwardly through said flue through the connecting passageway and down through the purifying chamber and into the room.

3. In an air-conditioning system, the combination with a room or other inclosed space, of a flue communicating at its lower end with the outer air, a purifying chamber arranged to communicate with the interior of the room at its lower end, a passageway connecting the upper end of said flue with the upper end of the purifying chamber, a series of superimposed and vertically spaced water-troughs arranged in said purifying chamber, the alternate troughs beginning at the upper end of the purifying chamber being arranged in proximity to one wall of the purifying chamber and the other troughs being arranged in close proximity to the opposite wall of the said purifying chamber, said troughs overlapping at the

center of said chamber, means for supplying water to the uppermost trough, overflow pipes connecting each trough with the next lower trough, means for separately 5 draining each trough and means arranged at the lower end of said flue for heating the air and producing a circulation of air upwardly through said flue, through the connecting passageway, down through the purifying chamber and into the room.

4. In an air-conditioning system, the combination with a room or other inclosed space, of a vertically arranged flue located at one 10 side of said room, said flue communicating 15 both with the outer air and the interior of said room, a purifying chamber arranged at the opposite side of said room, a passageway connecting the upper end of said flue with the upper end of the purifying chamber and 20 the lower end of said purifying chamber communicating directly with the interior of the room, a series of superimposed and vertically spaced water-troughs arranged in 25 said purifying chamber, the alternate troughs beginning at the upper end of the purifying chamber being arranged in proximity to one wall of the purifying chamber and the other trough being arranged in close proximity to the other wall 30 of the purifying chamber, means for supplying water to the uppermost trough, over-

flow pipes connecting each trough with the next lower trough, means for separately draining each trough and means for producing a circulation of air upwardly through 35 said flue through the connecting passageway down through the purifying chamber and into the room.

5. In an air-conditioning system, the combination with a room or other inclosed space, 40 of a purifying chamber communicating at both ends with the interior of said room, a series of superimposed vertically spaced water troughs arranged in said purifying chamber, the alternate troughs beginning at 45 one end of the purifying chamber being arranged in close proximity to one wall of the purifying chamber and the other troughs being arranged in close proximity to the opposite wall of the purifying chamber, said 50 troughs overlapping at the center of the said chamber and means for producing a circulation of air from the room through the purifying chamber and back into the room 55 again.

In testimony whereof, I sign the foregoing specification, in the presence of two witnesses.

LOUIS M. DU COMMUN.
